(57) **CLAIM**

The ornamental design for a current sensor, substantially as shown and described.

DESCRIPTION

FIG. 1 is a front top right perspective view of a current sensor, showing an embodiment of the design;

FIG. 2 is a front cross section view of the design of FIG. 1;

FIG. 3 is a rear cross section view of the design of FIG. 1;

FIG. 4 is a top isometric view of the design of FIG. 1;

FIG. 5 is a bottom isometric view of the design of FIG. 1;

FIG. 6 is a left side view of the design of FIG. 1;

FIG. 7 is a right side view of the design of FIG. 1;

FIG. 8 is a bottom front perspective view of the design of FIG. 1;

FIG. 9 is a left rear top plan view of the design of FIG. 1;

FIG. 10 is a rear top left plan view of the design of FIG. 1;

FIG. 11 is a front top right view of an alternative embodiment of the design;

FIG. 12 is a front view of the design of FIG. 11;

FIG. 13 is a rear view of the design of FIG. 11;

FIG. 14 is a top view of the design of FIG. 11;

FIG. 15 is a bottom view of the design of FIG. 11;

FIG. 16 is a left side view of the design of FIG. 11;

FIG. 17 is a right side view of the design of FIG. 11;

FIG. 18 is a bottom front right perspective view of the design of FIG. 11;

FIG. 19 is a right front top perspective view of the design of FIG. 11; and,

FIG. 20 is a back top left perspective view of the design of FIG. 11.

Shading lines shown in the drawings are intended to represent the approximate three-dimensional contour of the design, and are not intended to indicate surface decoration. The broken lines in the figures are for illustrative purposes only and form no part of the claimed design.
